DESIGN.

H. THIELE.

RAG CARPET.

No. 16,084.

Patented May 12, 1885.

UNITED STATES PATENT OFFICE.

HENRY THIELE, OF MILWAUKEE, WISCONSIN.

DESIGN FOR A RAG CARPET.

SPECIFICATION forming part of Design No. 16,084, dated May 12, 1885.

Application filed February 2, 1885. Term of patent 14 years.

To all whom it may concern:

Be it known that I, HENRY THIELE, a citizen of the United States, residing at Milwaukee, in the county of Milwaukee and State of Wisconsin, have invented and produced a new and original Design for Rag Carpets, of which the following is a specification, reference being had therein to the accompanying photograph, forming a part thereof.

10 My design relates to that class of carpets denominated "rag carpets," and it consists in certain peculiarities of ornamentation going to make up a pleasing and effective whole, as indicated by the accompanying photograph.

15 In my design I show a series of stripes, A A A, which consist of a number of checks or squares, $a a$ and $a' a'$, separated by horizontal stripes $a' a' a'$, extending entirely across the pattern, the effect of which is that the checks or squares $a a$, as well as the checks or squares $a' a'$ in diagonal line, do not join each other at their corners, as in a checker-board, but are interrupted or separated by the said horizontal lines $a' a'$. Each of the checks or squares $a a$ has the appearance of a light square, and each of the checks or squares $a' a'$ has the appearance of a darker square, producing the effect to the eye shown in the accompanying photograph; besides which, the independent threads in the squares a are in a different horizontal line from the threads in those squares a' which are in the same horizontal line with the squares a —that is, in each horizontal series of squares $a' a' a'$ the warp-threads in the squares a will show in different horizontal line from the warp-threads in the adjacent squares a' .

20 In addition to the stripes A A A, above described, I show the stripes B, B, C, and D, completing my design. The stripes B B each consist of a series of broken vertical stripes $b b b$ —that is, vertical stripes of unequal width corresponding in their alternations of width with the horizontal rows of checks or squares $a a'$, and having a central stripe, B', with diagonal lines on each side to simulate the appearance of a braid. The stripe C has two vertical stripes, $c c$, on its outer vertical sides, and these stripes are made up of the squares a and a' , al-

ready described, alternated and separated by the lines a' , and there is also a central vertical stripe, c' , composed of oblong checks $c' c'$ $c' c'$, arranged alternately one above the other, and separated by the horizontal lines a' , already 55 named. In the checks c' are seen upright light and dark lines, the light lines appearing to be the widest, while in the checks c' are similar vertical light and dark lines; but the dark lines appear to be the widest. The stripe D 60 is wholly composed of the hereinbefore-described broken vertical lines $b b$, and similar to the stripes B, except that it is without the described central stripe, B', with its diagonal lines in imitation of the appearance of a braid. 65 The stripes A, B, C, and D are all vertical composite stripes, as indicated by the photograph.

Having thus described and illustrated my new and original design, what I claim is— 70

1. In a design for rag carpets, the stripes A, consisting of the alternately-arranged checks or squares a and a' , divided or separated by the horizontal lines a' , of varying and unequal width, substantially as set forth and shown. 75

2. In a design for rag carpets, the stripes B, consisting of the vertical lines $b b$, of alternately-different widths, and the central stripe, B', with diagonal lines in simulation of the appearance of a braid, substantially as set forth 80 and shown.

3. In a design for rag carpets, the stripe C, consisting of the vertical outer stripes, $c c$, each composed of the alternately-arranged checks or squares a and a' , divided or separated by 85 the horizontal lines a' , of varying and unequal width, and the central stripe, c' , of the alternately-arranged oblong checks c' and c' , similarly divided by the lines a' , substantially as set forth and shown. 90

4. The design for rag carpets, consisting of the stripes A, B, C, and D, substantially as described, and shown in the accompanying photograph.

In testimony whereof I affix my signature in 95 presence of two witnesses.

HENRY THIELE.
